UNITED STATES PATENT OFFICE.

HARRY M. ABERNETHY AND HARRY D. ABERNETHY, OF CLEVELAND, OHIO.

COMBINED STATIONARY TRANSFORMER AND CONVERTER.

Application filed September 16, 1919. Serial No. 324,237.

To all whom it may concern:

Be it known that we, HARRY M. ABERNETHY and HARRY D. ABERNETHY, citizens of the United States, residing at Cleveland, in the county of Cuyahoga and State of Ohio, have invented certain new and useful Improvements in Combined Stationary Transformers and Converters, of which the following is a specification.

This invention relates to novel means for rectifying or converting an alternating current into a direct current; the alternating current, the polarity of which is reversing, is rectified or converted into a pulsating direct current, the polarity of which does not change or alternate, but continues to flow in one direction.

The prime object of our invention is to provide improved, novel and meritorious means of thorough efficiency which will serve to prevent the great losses that usually occur in converting an alternating current into a direct current, said latter current being used for any purpose for which it would be required.

A further object of the invention is to provide our improved means with a stationary transformer attached directly to the power lines, whereby the electro-motive force of the current to be rectified is reduced or amplified to that required.

Another object of this invention is to provide novel means for revolving the armature at a constant speed and in step, or synchronism with the alternations of a single cycle alternating source of supply, without using current, either alternating current or direct current in the armature coils.

The foregoing and such other objects as may appear from the ensuing description are attained by the combination, arrangement, location and novel features of the construction of the parts more fully hereinafter described, illustrated in the accompanying drawings and particularly pointed out in the claims appended hereto, it being understood that slight changes in the form, proportions, and minor details of construction may be resorted to without departing from the spirit or sacrificing any of the advantages of the invention.

In the accompanying drawings which form a part of the specification it will be seen that:

Figure 1 illustrates partly in longitudi-

nal section and partly in elevation the means embodying our invention.

Figure 2 is a front elevation of the apparatus shown in Figure 1.

Figure 3 is an end or rear view of Figure 1, with the lower portion broken away.

Figure 4 is a slightly reduced longitudinal section taken through the transformer core and showing the iron laminated core surrounded by the primary and secondary coils.

Figure 5 is a transverse section taken in the plane of the dotted lines 5-5, Fig. 1, with the primary and secondary coils of wire removed from the laminations of soft iron forming the solid core of the transformer.

Figure 6 represents a detail showing commutator P' Fig. 1; brushes S, S and swinging arms u and u' Fig. 3, and the wire connection from segments q, q leading to the armature winding.

Figures 7 and 8 are diagrammatic views.

Similar characters of reference are employed in designating corresponding parts throughout the several views of the drawings.

In carrying out our invention it will be seen that it comprises a transformer composed of a foot or rest A, Fig. 1, which may be bolted to a suitable base; two legs B consisting of a series of laminations made of soft iron punchings, insulated, and stacked together, and so arranged as to practically constitute a solid core of iron through which an alternating magnetic flux is caused to flow; a brass plate C is suitably secured to one side of said legs, and a primary coil D, Fig. 4, of insulated wire is wound directly around each leg of the laminated core, each primary coil being surrounded by a secondary coil E of insulated wire, said coils being connected by the wires c and c' respectively, as shown in Fig. 4.

a. Fig. 2, indicates the end of the bolts and nuts for securing the said laminated iron strips and brass plates in their proper position, and b are stud bolts with nuts to clamp another brass plate C', the latter being provided with slots b' to allow said plate to be adjusted and which is free to turn on its center support, this support being formed by an extension projecting from the brass plate at d, and describes a circle with plate C' surrounding and closely fitted thereon. D' represents the end of the ar-

mature shaft D^2 with nut adapted to bind tightly to the shaft. The brush holder F mounted on said shaft is provided with a wing portion or extension f at each side thereof, shown in Fig. 2, and is cast or molded as a single piece, each of said extensions f being adapted to carry a brush f' which is held in contact by a suitable spring which hooks or fastens around the 10 pin, as shown in the slot, Fig. 2, said brush traveling around and in contact with a ring G . This ring G is formed in six parts or sections, viz., 1'-2'-3'-4'-5'-6', these parts or sections being joined together with 15 an insulating substance, preferably mica, between each part, so that the six pieces are separately insulated from each other. Said ring G is then surrounded by an insulating substance h (Fig. 1) and held in the position 20 shown by a second ring I , which in turn is fixedly secured by the turned over extension j formed on the plate C' . A wire is attached to each one of the three longer segments of the ring G , one insulated wire being 25 shown at K . L is an oil ring bearing for the shaft D^2 supported by the brass plate. M indicates the armature core made up of soft iron punchings bolted together by the bolts m and surrounding the shaft D^2 , the 30 washer n serving to prevent their lateral movement and washer o their twisting or turning on said shaft. Since wire w is wound on this armature, the punchings are made as shown in Fig. 5, leaving room for 35 the wire. Each end of this wire is attached to a commutator carried by the shaft D^2 , as shown at P' , Fig. 1. This commutator and the brushes are shown in Fig. 6 which illustrates an end elevation showing the brushes 40 s, s' , carried by the swinging arms u and u' , which are supported by the rear brass plate V , Figs. 1 and 3, bolted to the opposite side of the transformer legs from that of the brass plate referred to in Fig. 2, the same 45 bolts a clamping to these legs the two plates. In Fig. 6 p indicates insulating material surrounded by the two brass segments g , and the armature wires being attached one each to these segments. 50 In Figs. 1 and 3, W represents a contact piece carried by an arm a' and insulated therefrom, which arm constitutes a part of a yoke a^2 (Fig. 3) supported by studs a^3 located near the rear shaft bearings B' (Fig. 55 1). V' is an extension formed on the rear brass plate V terminating in the support of bearing B' , and D^3 is a flanged sleeve made to slide laterally on the shaft (Fig. 1). Connected to this sleeve are two flat springs e , each spring carrying a weight g , the other end of these springs being made fast to the sleeve g' which does not move on the shaft. The yoke a^2 is engaged with the flanged sleeve D^3 (Fig. 1,) and the contact piece W 60 attached on the arm of said yoke, as shown 65

in Figs. 1 and 3, is held in suspension and above the two swinging arms u and u' , and on revolving the shaft the two weights g swing outward from the position shown, thus drawing the flanged sleeve D^3 along the 70 shaft, permitting the contact piece W to drop between the two extensions of the swinging brush holders u and u' , thereby automatically removing from contact with the commutator P' the two brushes s, s' , and 75 allowing the armature and shaft to revolve without contact in any way with said brushes. The two swinging arms u and u' are insulated from the plate V by the use of insulating material which surrounds their 80 stud supports h' and h'' . The yoke a^2 forming part of the arm a' carries an extension shown by dotted lines a^4 (Fig. 3), which is grooved or split, and the flanged sleeve D^3 revolves within this grooved or split extension, shown at a^5 , Fig. 1.

It will be perceived that our improved means provides a transformer having two legs, each leg being composed of laminations made of soft iron punchings, insulated, and 90 stacked up together, and so constructed and arranged as to constitute a solid iron core, a primary coil of insulated wire being wound directly around each laminated core and each primary coil being surrounded by a 95 secondary coil of insulated wire, or vice versa, and that our novel means is employed with a movable or revolving shaft and armature inserted in the path of the magnetic flux with the rate of speed fixed, predetermined and unchangeable without the aid of electrical energy in the armature windings, the rate of speed being constant and without variation, regardless of the amount of 100 induced current taken from the secondary coils leading to the stationary commutator segments, and revolving without being electrically connected; an automatic device for starting said armature and shaft from a single source of energy, for cutting off the flow 105 of current from the armature winding, when the shaft has reached a predetermined rotation or speed, for removing the armature brushes which constitute the conducting means of the energy to the armature windings and for closing the circuit through primary coils only, when the brushes are 110 removed.

The operation of the rectifier is as follows: Referring to Fig. 7. When the armature is stationary an electrical path is made from supply line to wire 1, swinging arm u' , brush s , commutator segment g , through armature winding w , opposite commutator segment g , brush s' , swinging arm u , wire 9, through primary coil D , connecting wire c , through primary coil D , wire 13, to supply line. When supply lines are energized by any suitable alternating supply, current flows through above described circuit caus- 115 120 125 130

ing armature to rotate as in ordinary series wound motor.

The weights g on the springs e , Fig. 1, are so adjusted that when the armature has reached a predetermined speed and is in exact step with the flow of the magnetic flux back and forth through the iron transformer core, the governor weights g are thrown outward by centrifugal force, drawing along the shaft the sleeve and collar D^3 . Inwardly projecting lugs or extensions on the yoke a^2 being engaged by the collar force the yoke to an inclined position, thus through the arm a' (Figs. 1 and 3) forcing the contact piece W between the two free ends of the swinging brush holders u and u' , which action swings the brushes clear of the commutator. (This movement shown better in Figure 3). This action cuts off all current from the coil surrounding the armature but armature continues to revolve due to the alternating magnetic flux. The current now flowing from supply line through wire 1— u' — W — u —9— D — c — D —13 to supply line. Should the armature fail to synchronize with the flux wave on the first effort, the speed of the armature would decrease causing the weights g to tend to assume their normal position, thus lifting contact piece W , and allowing the current to again flow through brushes and armature coil which would again speed up the armature. When the armature is running by this magnetic flux, it is in synchronism with the alternations of the power line. Thus we have a revolving armature and shaft kept in motion by the flow of the alternating magnetic flux through the iron of the transformer, across the gaps between the transformer iron and through the armature iron.

This device may be properly termed a synchronous machine for the reason that certain events are occurring at the same time, that is, the rectifying brushes are moving across the commutator segments currently in time with the alternations of the current.

The current to be rectified is induced in the secondary coils E by the alternating current flowing in the primary coils D , shown diagrammatically in Fig. 7, circuit of which primary coil has been previously described. The rectifying of the induced alternating secondary current takes place after the armature winding has been cut out of circuit by the lifting of brushes s' and s by contact piece W , as previously described, and the rectifying is accomplished by brushes f' and f held within and in electrical contact with brush holder F , Fig. 2, rotating in synchronous speed within stationary commutator C' and making intermittent contact between segments 4' and 6' and 5' and 6'.

The circuits are shown in Fig. 7, primary coils shown as D and secondary coils shown

as E . When brushes f' and f in their synchronous rotation have electrically connected segments 4' and 6' the induced electromotive force in secondary coil E is of such polarity as to cause a current to flow from coil E to wire 14 through resistance X , which represents any work that the rectified current may be required to perform, to segment 6' across brushes f' and f and brush holder F , diagrammatically shown as solid diagonal line, to segment 4' to wire 15 and to coil E . As the alternating current in the primary coils reverses in polarity, thereby causing electro-motive force in secondary coils to reverse in polarity the brushes and holder in their synchronous rotation have made contact between segments 5' and 6' thereby opening circuit from one secondary coil E and connecting the other coil E in circuit, the current from the last-named coil E flowing through wire 14, work X , segment 6', across brushes and holder, shown as diagonal dotted line, segment 5', wire 16 to the last-named coil E . Thus a circuit flowing in one direction only is maintained in work X .

Referring to Figure 2, it will be seen that commutator C' is provided with slots b' , b' , which permit commutator to be rotated around its center, after screws b and b' are loosened, thus providing a means of adjusting the commutator so that the brushes pass off segments 4' and 5' at that instant that the flow of current has ceased and before the current can flow in the opposite direction, due to reversal of electro-motive force.

Figure 8 shows another method of connecting the secondary coils to the work circuit, Figure 7 showing connections by which one secondary coil is producing current for the entire work circuit during one-half cycle while Figure 8 shows work circuit divided in two separate parts and both secondary coils producing current simultaneously. Circuits are as follows:

When brushes and holder are in contact with segments 4' and 6' current flows from secondary coils E through connecting wire c' , coil E , wire 1'', segment 6', brushes and holder F' , segment 4', wire 2'', work X' , wire 3, to coil E . When current in secondary coils reverses in direction brushes and holder are connecting segments 5' and 6' and current flows from the other coil E through connecting wire c' , coil E , wire 3, work X^2 , wire 5'', segment 5', brushes and holder, represented by dotted diagonal line, segment 6', wire 1'' to coil E . This method divides the work in two parts but directs the flow of current in each part in the same direction.

It will be observed that our improved apparatus is provided with suitable covers to prevent access of dust and other foreign matter to the working parts thereof.

Having thus described our invention, what

we claim and desire to secure by Letters Patent is:

1. An apparatus of the character described comprising a stationary transformer having stationary primary and secondary coils with an iron core, in combination with a revolvable shaft, an armature formed of a series of soft iron laminations mounted on said shaft, a commutator mounted on said shaft, swinging brushes adapted to contact with said commutator, automatically operated means mounted on said shaft and adapted to disconnect the brushes from the commutator, and means for revolving said shaft and armature at a fixed, predetermined and unchangeable speed while the armature windings are free of electrical energy.
2. An apparatus of the character described comprising a stationary alternating current transformer having stationary primary and secondary coils, a revolvable shaft, an armature mounted on the shaft and disposed in the transformer core, automatically operated means for starting said armature and shaft from a single source of energy, and automatically operated means mounted on said shaft for cutting off the flow of current from the armature winding when the shaft has reached a predetermined speed of rotation.
3. An apparatus of the character described comprising a stationary transformer having stationary primary and secondary coils with an iron core, in combination with a revolvable shaft and disposed in the transformer core, an armature mounted on said shaft, direct current commutator brushes mounted on the shaft at one side of the armature, an automatic device for starting the armature and shaft from a single source of energy, and automatically operated means

mounted on said shaft for cutting off the flow of current from the armature winding and maintaining the current through the primary coils.

4. An apparatus of the character described comprising a stationary alternating current transformer having stationary primary and secondary coils, a revolvable shaft, an armature mounted on said shaft and disposed in the transformer core, direct current commutator brush holders mounted on the shaft at one side of the armature, direct current brushes carried by said holders, automatically operated means carried by said shaft for starting said armature and shaft from a single source of energy, and automatically operated means mounted on said shaft for cutting off the flow of current from the armature winding when the shaft has reached a predetermined rotation.

5. An apparatus of the character described comprising a stationary alternating current transformer having stationary primary and secondary coils with a core formed of a series of soft iron laminations, a revolvable shaft, a revolvable armature mounted on said shaft formed of a series of soft iron laminations with wire windings, direct current commutator brushes and holders mounted on the shaft at one side of the armature, automatically operated means for starting said armature and shaft and automatically operated means mounted on said shaft for cutting off the flow of current from the armature windings when the shaft has reached a predetermined speed of rotation, said armature being mounted in the path of the magnetic flux which flows through the iron core.

HARRY M. ABERNETHY.
